UNITED STATES PATENT OFFICE

140,794

DESIGN FOR A MAGNETIC DIRECTION INDICATOR

Gabriel M. Giannini, West Los Angeles, Calif., assignor to Autoflight Corporation, Burbank, Calif., a corporation of Delaware

Application August 8, 1944, Serial No. 114,784

Term of patent 7 years

(Cl. D52—1)

To all whom it may concern:

Be it known that I, Gabriel M. Giannini, a citizen of the United States, residing at 670 Ledo Way, West Los Angeles, in the county of Los Angeles and State of California, have invented a new, original, and ornamental Design for Magnetic Direction Indicator, of which the following is a specification, reference being had to the accompanying drawing, forming part thereof.

Fig. 1 is a front perspective view of a magnetic direction indicator, showing my new design;

Fig. 2 is a rear-and-side perspective view of the same.

The drawing is shaded to indicate contrasting appearance. The side of the design opposite to that shown in Fig. 2 is the same as that shown in that figure.

I claim:

The ornamental design for a magnetic direction indicator, as shown and described.

GABRIEL M. GIANNINI.
